(57) **CLAIM**

The ornamental design for a microcurrent skin treatment device as shown and described.

DESCRIPTION

FIG. 1 is a top, right side, front, perspective view of a microcurrent skin treatment device showing my new design; FIG. 2 is a bottom, left side, rear, perspective view of the microcurrent skin treatment device illustrated in FIG. 1; FIG. 3 is a top plan view of the microcurrent skin treatment device illustrated in FIG. 1; FIG. 4 is a right side elevation view of the microcurrent skin treatment device illustrated in FIG. 1, the left side elevation view of the micro-current delivery device is a mirror image thereof;

FIG. 5 is a front elevation view of the microcurrent skin treatment device illustrated in FIG. 1;

FIG. 6 is a bottom plan view of the microcurrent skin treatment device illustrated in FIG. 1; and,

FIG. 7 is a rear elevation view of the microcurrent skin treatment device illustrated in FIG. 1.

The dashed broken lines in the FIGS. 1 through 7 represent portions of the microcurrent skin treatment device that form no part of the claimed design.

1 Claim, 7 Drawing Sheets
